(57) **CLAIM**

The ornamental design for a shoe, as shown and described.

DESCRIPTION

FIG. 1 is a perspective view of a shoe;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a back view thereof.

The broken lines depict portions of the shoe related to switching that form a part of the claimed design.

The dot-dash-dot lines depict portions of the shoe which form no part of the claimed design.

1 Claim, 7 Drawing Sheets# US D991,638 S
